UNITED STATES PATENT OFFICE.

GEORGE W. FERGUSON, OF PHILADELPHIA, PENNSYLVANIA.

FASTENER FOR DRESS-SHIELDS.

SPECIFICATION forming part of Letters Patent No. 645,077, dated March 13, 1900.

Application filed July 22, 1899. Serial No. 724,739. (No model.)

To all whom it may concern:

Be it known that I, GEORGE W. FERGUSON, a citizen of the United States, residing in the city and county of Philadelphia, State of Pennsylvania, have invented a new and useful Improvement in Fasteners for Dress-Shields, which improvement is fully set forth in the following specification and accompanying drawings.

10 My invention relates to an improved construction of a fastener which is capable of various applications, but is adapted to be especially used for the purpose of securing a dress-shield in position; and it consists of a 15 plurality of plates or disks, one of which latter is rotatably mounted upon a movable bar having a spur or other fastening means thereon, while the other of said plates is also provided with fastening means, said rotatable 20 plate being recessed, so as to be readily opened when in the proper position, and being provided with spurs at the terminals of said recess. Thereby said plate can be turned and locked in the desired position relative to 25 said bar.

It further consists of novel details of construction, all as will be hereinafter fully set forth, and particularly pointed out in the claims.

30 Figure 1 represents a plan view of a blank from which one of the plates or members of the fastener is produced. Fig. 2 represents a plan view of the other plate or member of the fastener. Fig. 3 represents a plan view 35 of the plates or members in assembled position, one of said plates being opened or turned at a right angle to the other plate. Fig. 4 represents a side elevation of Fig. 3. Fig. 5 represents a section on line $x-x$, Fig. 3. Fig. 40 6 represents a plan view of the fastener, showing the same in closed position. Fig. 7 represents a view similar to Fig. 6 by showing the rotatable plate turned and locked in the desired position. Fig. 8 represents a perspective view of a dress-shield in position in a 45 dress, showing also the application of my improved fastener thereto.

Similar letters of reference indicate corresponding parts in the figures.

50 Referring to the drawings, A designates the blank from which one of the plates or members of the fastener is produced, said blank

consisting of the body portion B, which is preferably disk-shaped and has the member C extending therefrom at substantially a right angle thereto; said member being provided with the extension D, which is bent nearly parallel to the plate B and has the slot E therein, said portion D being doubled upon itself, as will be understood from Figs. 3, 4, 55 5, so as to form a support, in which is hinged the strip or bar F, the latter being pivotally secured in position at the point G, whereby the members C and F can open and close forwardly to move their opposing faces 60 65 away from and toward each other.

H designates the other plate or member of the fastener, the same being pivotally mounted upon the bar F at the point J and being provided with a recess K, said plate when in 70 the position seen in Figs. 3 to 6, inclusive, being adapted to be readily moved toward or away from the plate B.

L designates spurs which project inwardly from the plate H, either of said spurs being 75 adapted to retain the plate H when the latter is turned into the position seen in Fig. 7, or vice versa, the contiguous spur L engaging with the portion D, as is evident.

M designates spurs which project from the 80 plate B, the same being two or more in number and being located oppositely to the spur N, which projects from the bar F.

P designates a dress-shield and the dotted line Q the point of application of the latter to 85 a dress.

The operation is as follows: In order to apply the fastener, the same is opened, so that the parts assume the position seen in Figs. 3, 4, and 5. The dress-shield having been placed 90 in position relative to the sleeve of the dress, as indicated in Fig. 8, the fastener is placed thereupon, the portion C contacting with the folded portion of the shield, whereupon the points or spurs M M are forced into the material. The plate H and bar F are then turned 95 upon the hinge or pivot until the same are parallel or closed, the parts then appearing substantially as seen in Fig. 6, the spur N being forced into the material. The plate H 100 is next turned into the position seen in Figs. 7 and 8, the desired spur L riding over the portion D and snapping into the position seen in Fig. 7. When the spurs L ride over the

portion D, the plate H bends outwardly, and thus retracts said spurs from engagement with the material from the shield. When the spurs snap into the position shown in Fig. 7, they 5 reengage the material of the shield, it being apparent that when the parts are in the position seen in Fig. 7 the plate H is practically immovable with respect to the bar F or the opposite plate and the shield is held firmly 10 and exactly in the desired position. To remove the shield or the fastener, it is only necessary to turn the plate H from the position seen in Fig. 7 to the position seen in Fig. 6, whereupon said plate can be readily 15 turned into the position seen in Figs. 3, 4, and 5 and the fastener can be removed.

It will thus be seen that by my invention I produce in a cheap and practical manner a fastener which is capable of being used for 20 various purposes, but especially for fastening dress-shields in position, and which can be readily applied to and disengaged from the material to which it is attached according to requirements.

25 Having thus described my invention, what I claim as new, and desire to secure by Letters Patent, is—

1. A fastener consisting of pivotally-connected members adapted to open and close forwardly, devices on the inner sides of said 30 members to engage material situated between the same when the members are closed, and a rotary locking device mounted upon one member adapted to engage and lock the other 35 member when the members are closed.

2. A fastener consisting of pivotally-connected members adapted to open and close forwardly, devices on the inner sides of said members to engage material situated between 40 the same when the members are closed, and a rotary locking device mounted upon one member adapted to engage and lock the other member when the members are closed, said locking device being provided on its inner 45 side with devices for engaging the material held by said fastener.

3. A fastener consisting of a member having a projecting portion, a member pivotally mounted upon said projecting portion, whereby said members are adapted to open and close forwardly, devices on the inner sides of said members to engage material situated between the same when the members are closed, and a rotary locking device mounted upon the second-mentioned member and adapted to engage said projecting portion of the other member when the members are closed. 55

4. A fastener consisting of a member having a projecting portion, a member pivotally mounted upon said projecting portion, whereby said members are adapted to open and close forwardly, devices on the inner sides of said members to engage material situated between the same when the members are closed, and a rotary locking device mounted upon the 60 second-mentioned member, said locking device having a recess to receive said projecting portion and with a projection to engage the same. 65

5. In a fastener, a plurality of plates, one of 70 the same having spurs attached thereto and being provided with a deflected portion, having a bar pivotally attached thereto, a plate rotatably mounted upon said bar and provided with a recess therein, the terminals of 75 said recess being deflected so as to form locking devices.

6. As an improved article of manufacture, a fastener consisting of a plate having spurs attached thereto, a portion of said plate being deflected so as to form a bearing for a bar movably attached thereto, said bar carrying a spur, a plate rotatably mounted upon said bar and provided with a recess therein, the terminals of said recess being deflected 80 so as to form a locking means for said plate when the latter is turned in either direction 85 into the desired position.

GEORGE W. FERGUSON.
